United States Patent Office

Des. 226,263
Patented Feb. 6, 1973

226,263

MOBILE HOME OR SIMILAR ARTICLE

William Bizzaro, Jr., 10 Huron Drive,
Hudson, Mass. 01749

Filed Jan. 4, 1971, Ser. No. 103,962

Term of patent 14 years

Int. Cl. D12—10; D25—03

U.S. Cl. D14—3 E

FIG.1

FIG.6

FIG. 1 is a top plan view of a mobile home or similar article, showing my new design;

FIG. 2 is a perspective view thereof;

FIG. 3 is a side elevational view looking from top to bottom at FIG. 1;

FIG. 4 is an end elevational view looking from right to left at FIG. 1;

FIG. 5 is an end elevational view looking from left to right at FIG. 1; and

FIG. 6 is a side elevational view looking from top to bottom at FIG. 1.

I claim:

The ornamental design for a mobile home or similar article, substantially as shown.
